UNITED STATES PATENT OFFICE.

JAMES COOKE, OF OMAHA, NEBRASKA.

MEANS FOR MOUNTING AND CUTTING LABEL-HOLDER CHANNELS.

Application filed July 14, 1924. Serial No. 725,923.

To all whom it may concern:

Be it known that I, JAMES COOKE, a citizen of the United States, residing at Omaha, in the county of Douglas and State of Nebraska, have invented certain new and useful Improvements in Means for Mounting and Cutting Label-Holder Channels, of which the following is a specification.

My invention relates to metal cutting and forming devices, and it is the object thereof to provide a simple, compact and efficient mechanism for applying label-holding channels to the wooden blocks or mounts commonly used for rubber hand-stamps. My present invention is intended particularly for use in connection with label-holders of the character described in Letters Patent No. 1,511,028, issued to me October 7, 1924, with which the label-holding channel-bar is formed in long pieces provided at uniform intervals with integral tongues adapted to be driven and clinched in wood or like material. A particular object of my invention is to provide a device adapted to shear off from a channel-shaped bar sections or pieces which have been previously affixed to a block, the shearing operation serving to close or crimp down the flanges of the channel-bar at the end of the sheared-off piece, while the channel is kept open at the end of the main piece.

Mechanism embodying my invention is illustrated in the accompanying drawings, in which Fig. 1 is a front view thereof, Fig. 2 is a partial longitudinal section on the line 2-2 of Fig. 7, Fig. 3 is a detail plan view of the holder-block, Fig. 4 is a side view of the same, partially in section on the line 4-4 of Fig. 3, Fig. 5 is a detail transverse section of the label-holding channel-bar, Fig. 6 is a plan view of the entire mechanism, and Fig. 7 is a vertical section on the line 7-7 of Fig. 6.

In the structure illustrated I provide a metal base-plate 8 adapted to be attached by screws 9 to a table or bench, and upon the central part of said base-plate, extending longitudinally thereof, is secured the anvil-bar 10. A hammer or bumper-bar 11 is arranged above said anvil-bar, so that its lower surface extends parallel therewith, said bumper-bar being carried at the lower end of a vertical rod or stem 12 which passes slidably through a guide 13 on a standard 14. The base of the latter is secured to the plate 8 behind the central part of the anvil-

bar, and the front face of the standard has a flat guide-surface against which the rear side of the bumper-bar rests slidably. A coil spring 15 is arranged around the stem 12 above the guide 13, said spring engaging the hand-knob 16 at the upper end of the stem and holding the bumper-bar normally in the raised position shown in Fig. 1. By striking the knob 16 the bumper-bar is forced downwardly toward the anvil-bar so as to forcibly engage any object placed between said members. An annular cushion 17, of rubber or the like, is preferably placed around the stem 12 beneath the guide to prevent the head of the bumper-bar striking the guide upon the upward or return strokes thereof. The lower portion of the standard 14 has an opening 18 therein, for a purpose which will presently appear.

The holder-block 19 is secured to the base 8 at one end thereof, said holder-block being at right angles to the anvil-bar and slightly spaced from one end thereof. Adjacent to and in alinement with the anvil-bar, the holder-block is recessed to receive the mandrel 20, which is secured in the recess by means of a screw 21. At the inner end thereof, adjacent to the anvil-bar, the mandrel has laterally projecting flanges 22 adapted to fit slidably within the U-shaped side-flanges B of the label-holding channel-bar A, the sectional form of which is clearly shown in Fig. 5. Said flanges 22 are of full width at the inner end-face of the mandrel, adjacent to the anvil-bar, and for a short distance back from said end-face, thence being beveled inwardly and terminating at the sides of the mandrel-body intermediate its ends, as shown clearly in Fig. 3. The holder-block 19 is grooved about said flanges 22 to provide a sufficient space for the flanges B of the channel-bar A to pass slidably between the sides of the groove and said mandrel-flanges at the ends where said flanges are of full width, the grooves 23 of the block being extended entirely across the same to the outer side. The upper surface of the mandrel is at the same level as the upper surface of the anvil-bar, and the width of the anvil-bar is such that the inturned edges of the flanges B may fit slidably against the sides of the bar.

In the use of the mechanism, a long piece of the channel-bar A is engaged with the mandrel by first laying the end of the channel-bar upon the outer or unflanged end of

the mandrel, so that the flanges B lie within the grooves 23 in the block 19, and then sliding the channel-bar inwardly so that its flanges pass about the mandrel-flanges 22. 5 By continued inward sliding movement of the channel-bar, it emerges from the end of the mandrel and passes out over the anvil-bar, the flanges B overhanging at the sides thereof, and the tongues C of the channel-bar extending upwardly as indicated in Figs. 1 and 2. In the anvil-bar there are a series of holes 38 indicated in Fig. 1, adapted to receive a gage-pin 39, against which the end of the channel-bar A may be engaged to limit the length of said bar which may extend out over the anvil-bar. Said holes 38 are positioned nearer to one side of the anvil-bar than to the other, as indicated in Fig. 6, so as to be engaged by a portion 10 of the channel-bar at one side of the perforations therein formed by the punching out of the tongues C. 15

The holder-block 19 is removably secured to the base-plate 8 by means of a screw 24, 20 the block being prevented from turning about the axis of said screw by a pair of vertical guide-posts 25 which are fixedly mounted upon the base, and which extend through holes in the block adjacent to the 25 ends thereof. The block is slideable upon said guide-posts, so as to be readily removed from the base after taking out the screw 24. On the upper portions of the guide-posts is 30 slidably mounted the clamp-block 26, there being coil springs 27 disposed around the posts between said clamp-block and holder-block, said springs extending into counterbores or cylindrical recesses formed in the adjacent faces of the blocks concentrically 35 with the posts. The springs 27 are so proportioned as to normally hold the clamp-block in the raised position shown in Figs. 1, 2 and 7, but are compressible so as to lie wholly within the counterbores, whereby the 40 adjacent faces of the blocks may be moved into contact with each other. At the inner side of the clamp-block the shear-plate 28 is secured thereto, said plate being so proportioned and arranged that its inner side is 45 flush with or in the same vertical plane as the inner side of the holder-block and the inner end of the mandrel 20. The upper portion of the shear-plate is spaced from an upwardly extending lug on the clamp-block 50 26, and between the same is arranged the lever 29, which is pivotally connected therewith by means of a shouldered bolt 30, as best shown in Fig. 2. The lever 29 is normally in the diagonal position shown in Fig. 55 7, being provided at its front end with a handle 31, and at its rear end being connected with a tension spring 32, the latter extending downwardly and being connected with a hook 33 at the rear edge of the base-plate. The bar or link 34 is pivotally con-

nected with the lever 29 intermediate the rear end thereof and the pivot-bolt 30. The lower end of said link 34 is pivotally connected with the rear end of the shear-blade 35, which extends along the inner side of the 70 holder-block 19 and is pivotally connected therewith near the front end by a screw 36. The thickness of the shear-blade is such that it fits slidably between the holder-block and the end of the anvil-bar. The upper part of 75 the blade, at the intermediate portion which lies between the ends of the mandrel 20 and the anvil-bar, is beveled to form a cutting edge adjoining the mandrel. In said beveled portion of the blade there are two rectangular notches 37 which are aligned with the grooves or recesses 23 of the holder-block, as shown in Fig. 7, and between the bevel-edged portion and the pivot-screw 36 the upper edge of the blade is deeply recessed or cut away, as shown, to provide clearance for certain special forms of stamp-mounts sometimes used.

The lower edge of the shear-plate 28 is slightly recessed above the mandrel 20, as 90 shown in Fig. 7, so that when the clamp-block is engaged with the holder-block there will be a sufficient clearance between the shear-plate and mandrel to receive the body of the channel-bar A, and the central part of said recessed lower edge of the shear-plate is beveled to form a cutting edge 40 at the side thereof which is in register with the end of the mandrel. The lower side of the clamp-block has a groove or recess therein 95 above the mandrel, the purpose of said groove being to provide clearance for the tongues C of the channel-bar when such tongues chance to be beneath the clamp-block during the shearing operation. 100

As before mentioned, the described mechanism is intended and particularly adapted for applying to the wooden blocks or mounts, commonly used for rubber hand-stamps, label-holding channel-bars of the character shown in my co-pending application hereinbefore identified. The stamp-blocks or mounts D are of various widths and lengths, but are of substantially uniform thickness, the latter being approximately the same as the width of the channel-bars A. Handles E are attached to the central part of the blocks or mounts D, the size of the handles differing but slightly for all sizes of the mounts. In the use of the mechanism the gage-pin 39 is employed when a number of the mounts D of the same length are to have the label-holders applied thereto, said gage-pin being placed in one of the holes 38 such that the mount will be approximately centered with the bumper-bar when the end of the mount is engaged with the gage-pin. Ordinarily the label-holders are applied to the mount-blocks before the stamp or cushion is attached to the same, and in such case 110

the lateral position of the mount-block with respect to the anvil-bar is gaged by placing the bottom side of the mount-block, or that opposite the handle E, against the front face 5 of the standard 14, as represented in Figs. 1 and 6. When the stamp or cushion has been attached to the mount-block before the label-holder is applied, the position of the block is reversed from that shown in said 10 figures, the handle E being extended back through the hole 18 in the standard 14, and the position of the block is gaged by the contact between the face of the standard and the top of the block, or the side to which 15 the handle E is attached. Prior to the placing of the mount D beneath the bumper-bar, the channel-bar A is inserted and pushed in along the anvil-bar until its end engages the gage-pin 39, so that when the mount-block is 20 placed thereon said gage-pin serves to accurately register the end of the block with the end of the channel-bar. While the mount-block is held in gaged position the hand-knob 16 may be sharply struck one or 25 more times to drive the bumper-bar down against the upper edge of the block, and thereby force the latter against the tongues C of the channel-bar, so that said tongues penetrate the mount and become clinched 30 therein, as represented in Fig. 1. Then the mount and the attached channel-bar are moved along the anvil-bar until the end of the mount is engaged with the side of the shear-plate 28, after which the handle 31 of 35 the operating-lever 29 is pushed down. The strength of the springs 27 and 32 is so proportioned that the initial movement of the lever is about the fulcrum formed by its pivotal connection with the upper end of 40 the link 34, so that the shear-plate 28 and clamp-block 26 are moved downwardly until the latter engages the upper side of the holder-block 19. During such movement the sharpened lower edge 40 of the shear-plate 45 will cut through the tongues C, should any of the same be located in the shearing-plane, and at the conclusion of this portion of the operation the body of the channel-bar A is confined at all sides in the shearing-plane, 50 the inside of the channel being filled with the mandrel and its flanges 22, the outer sides of the channel-flanges B being confined by the holder-block 19, and the back or upper side of the channel-bar being confined 55 by the shear-blade. Then by further downward movement of the handle 31, the lever 29 moves pivotally about the bolt 30, so that the link 34 and the rear end of the shear-blade 35 are raised thereby. As the shear-blade 60 is raised the beveled cutting edge thereof shears off the entire portion of the channel-bar A which is attached to the mount-block D, and at the same time turns inwardly the corners of the flanges B so as 65 to substantially close the ends of the spaces within said flanges at the sheared end. The turning in of the flange-corners is effected because of the notches 37, which are so located that the corners of the cutting edge of the shear-blade, at the adjacent sides of 70 the grooves or notches 37, engage the channel-flanges B near the edges thereof, shearing the same and turning them inwardly before the blade engages and shears off the remaining body-portion of the channel-bar. The 75 main body of the channel-bar A, which remains clamped between the holder-block, mandrel, clamp-block, and shear-plate, is preserved in its original sectional form, because of its being supported at all sides by 80 said members. Thus one end of each piece of the channel-bar which is sheared off is kept open for the insertion of the label therein, while the flanges are turned in at the other end to prevent the label from passing 85 through the channel at said end. The advantage of this will be more clearly apparent when the same is considered in connection with the machine for labelling hand-stamps, disclosed in my companion application filed 90 herewith.

After the operation of the shearing devices to cut off a piece of the channel-bar A, and when the lever 29 is released, the springs 32 and 27 raise the lever and the clamp-block 95 to their normal or initial positions, so that there is clearance above the mandrel for the tongues C to pass the shear-plate 28 when the next section of the channel-bar A is to be 100 pushed out over the anvil-bar.

For applying the label-holders to single mounts, it is unnecessary to set the gage-pin 105 39, and the mount and channel-bar may be placed with their ends in register by mere inspection.

When the label-holders are to be applied to mount-blocks which already have the stamp or cushion attached thereto, so that the handle E must be inserted through the opening 18 in the standard as before described, a piece of the channel-bar A of the proper length is first sheared off and then slid along the anvil-bar to a position beneath the mount-block before the bumper-bar is operated to drive the tongues C into 110 the block and thus attach the channel-bar to the block.

Now, having described my invention, what I claim and desire to secure by Letters Patent is:

1. In a mechanism of the class described, a mandrel adapted to fit within the channel-bar, a holder-block carrying said mandrel and grooved to receive the flanges of the channel-bar, clamping means engageable 115 with the back of the channel-bar, said means and the holder-block and mandrel having faces alined in a plane transverse to the channel-bar and said members fitting about all sides of the channel-bar in said plane, 120

and a shear-blade having a cutting edge movable in said plane to cut off portions of the channel-bar projecting therefrom.

2. A shearing mechanism for channel-bars of the class described, comprising holding members adapted to fit about the channel-bar both inside and outside whereby to inclose the same transversely in a common plane, and a blade having a cutting edge movable in said plane to shear off portions of the channel-bar projecting from said holding members.

3. In a mechanism of the class described, a holder-block grooved to receive the channel-bar, a mandrel affixed to the holder-block and adapted to fit within the channel-bar, a movable clamping-member having a shear-plate thereon adapted to engage the back of the channel-bar upon the mandrel, said shear-plate having a face alined with the faces of the mandrel and holder-block, a shear-blade having a cutting edge at said alined faces movable past the end of the channel-bar groove therein, and an operating-lever connected with the clamping-member and shear-blade and arranged to actuate the same successively.

4. A shearing mechanism for channel-bars of the described class, comprising separable holding-members adapted to fit about the channel-bar to inclose the same transversely in a common plane, a shear-blade having a cutting edge movable in said plane to shear off portions of the channel-bar projecting from said holding-members, and an operat-

ing-lever connected with said shear-blade and one of the clamping-members and movable to first close the clamping-members upon the channel-bar and to then actuate the shear-blade to sever the portion of the channel-bar projecting from the clamping-members.

5. A structure as set forth in claim 3, in which the movable clamping-member is grooved to provide clearance for the attaching-tongues of the channel-bar, and the shear-plate has a sharpened edge adapted to cut through said tongues as the clamping-member is closed upon the channel-bar.

6. A structure as set forth in claim 4, in which the cutting edge of the shear-blade is notched to crimp in the flanges of the channel-bar at the end of the severed portion thereof.

7. A structure as set forth in claim 1, including an anvil-bar alined with the mandrel and arranged to support the portions of the channel-bar which project from the clamping means.

8. A structure as set forth in claim 1, including an anvil-bar alined with the mandrel and arranged to support the portions of the channel-bar projecting from the clamping-means, and means for pressing mount-blocks toward said anvil-bar to affix the same to said projecting portions of the channel-bar while said portions are unsevered from the clamped portions thereof.

JAMES COOKE
